ERASER AND HOLDER THEREFOR

Howard Edwin Griffin, Kew Gardens, and Vincent John Collins, Richmond Hill, N. Y.; said Griffin assignor to said Collins

Application February 17, 1948, Serial No. 8,776

1 Claim. (Cl. 120—36)

1

Our invention relates to rubber erasers, and more particularly to erasers used in connection with the operation of typewriters.

The object of this invention is to provide an eraser that may be easily accessible to a typist or other operator of a typewriter machine. This object is attained by having an eraser, preferably circular in shape, contained in a holder; said holder in addition to having said eraser incorporated therewith, has also a magnetic metal or alloy included in said holder; said magnetic metal or alloy having an attraction to iron or steel objects and being integral to said eraser will cause said eraser to attach itself to such an object as a typewriter frame casting or wall, said frame or wall being generally made of iron or such like ferrous metal or alloy.

A further object of this invention is to provide a holder for said eraser, said holder enabling replacement for said rubber eraser when it shall be worn down to the point that there is no usable eraser material projecting outwardly from said holder.

A further object is to furnish in combination a holder to contain a rubber or like eraser, combined with a permanent magnet, and also incorporating therewith a brush projecting from said holder and in convenient position relative to the position of said rubber eraser; said brush to remove eraser and paper dust after erasures have been made on typewritten copy generally incident to the process of operating a typewriter machine.

These and other objects will be seen as the description of the invention proceeds.

In the following detailed description we shall refer to the accompanying drawings in which:

Fig. 1 is an enlarged side elevation of the eraser and holder therefor, also showing the position of the permanent magnet metal or alloy;

Fig. 2 is a side cross-section view of said eraser and holder therefor on the line 2—2 of Fig. 1;

Fig. 3 is a detail view on the line 3—3 of Fig. 1 showing the position of the brush protruding through the holding collar arrangement of said brush; and

Fig. 4 is a stamping or stamped blank which is bent in two at the center portion thereof and when so bent, formed and secured, holds the eraser therein, and also enables said eraser to freely revolve in said holder.

Referring to the drawings, the designation 10 is a rubber eraser or eraser material of like properties which is held in the upper portion 16 of

5 the eraser holder 11, said holder being bent over at the position in Fig. 4 designated as 11a. The holder is formed of a metal sheet stamping or similar sheet material such as plastic sheeting capable of being bent over in the manner described.

The brush 12 is of the usual bristle hair type and is set into the slot opening 13 as shown in detail in Fig. 3. Said brush 12 is held securely 10 in position by the neckpiece or collar 14.

The permanent magnet 14a is circular in conformation and cross-section thereof somewhat less than that of the cross-section of said rubber eraser, and is made preferably of such iron-nickel-cobalt alloy known to the trade as Alnico, which alloy having high intensity magnetization, retaining the same for long periods of time.

Said permanent magnet 14a is set in position in a circular aperture in the eraser 10 between the 20 portions 15 and 16 of the holder 11, as shown in Fig. 2.

In Fig. 2 there is also known the manner in which the upper holding portions 15 and 16 of the holder 11 may be spread apart to permit the 25 placement in position of both the eraser 10 and the permanent magnet 14a. The portions 15 and 16 are shown spread apart in broken line.

After the rubber eraser 10 and the permanent magnet 14a, which is positioned in a round opening in said eraser, have been placed in position 30 as stated, the two portions 15 and 16 are permitted to spring back into normal position resting resiliently against said eraser and permanent magnet which is held thereto.

Referring to Fig. 2, said figure showing the 35 combination eraser, permanent magnet and brush holder in cross-section, it will be seen that the cross-section area of the permanent magnet is somewhat less than the cross-section of the eraser 10. This difference in cross-section provides a means of securing said eraser and permanent magnet to the holder 11 by reason of the circular shoulders 15a of the portions 15 and 16, which circular shoulders or beads press inwardly 40 against the outer surface of the permanent magnet and the central area of said eraser as shown in the figure.

It will thus be seen that by the incorporation of a permanent magnet in the eraser holder as described, said holder may always be within easy reach by being attached magnetically to the casing or wall of the typewriter and in this manner would not be so apt to be mislaid or lost.

55 In the event of a typewriter machine having

an aluminum or similar non-ferrous frame, a piece of sheet iron or like ferrous metal may be attached to the typewriter frame and thus provide a wall medium for the holder to be magnetically held thereto.

In the description of our invention we do not wish to confine ourselves to the shape of the rubber eraser which in this case is shown to be circular. The eraser may be made in other shapes within the eraser holder; such erasers may be square, triangular or oblong in shape.

It is further obvious that other modifications are possible in our invention from that described in this specification without departing from the spirit thereof, and we therefore do not limit ourselves to the literal description herein made, being only limited to the scope of the appended claim.

What we claim is:

In a device of the class described, a holder 20 of bendable sheet material and having circular portions at each end thereof, said holder bent over at the approximate center thereof forming

two bent over sections to provide a space in between said bent over sections, an eraser having an opening therein, a permanent magnet in said opening, said eraser mounted in the space between said bent in sections, said circular portions having a circular bead or shoulder fitting conformingly and resiliently in said opening of said eraser and against said magnet enabling the free rotation of said eraser held between said circular portions of said holder.

HOWARD EDWIN GRIFFIN.
VINCENT JOHN COLLINS.
